PUMP

Frank L. Davis, Jr., Kenilworth, N. J., assignor
to The Watson-Stillman Co., Roselle, N. J., a
corporation of New Jersey

Application December 14, 1934, Serial No. 757,425
Renewed July 29, 1937

8 Claims. (Cl. 103—173)

This invention relates to multi-cylinder, continuous delivery pumps and more particularly to hydraulic pumps of a type wherein the pump plungers are operated by a swash plate to deliver fluid at high pressure for operation of a press or other mechanism.

Important objects of the invention are, to provide such a pump of generally improved design; to provide for easy accessibility of the working parts of the pump mechanism and facilitate adjustment, repair and replacement of the parts; to provide an improved driving mechanism for the pump plungers; to provide an improved embodiment of the pump cylinder, plungers and valves in a unit, and to provide an improved organization of the driving mechanism and pump unit enabling the latter to be readily detached from the driving mechanism and readily replaced and also enabling pump units of different capacity to be connected interchangeably to the driving mechanism.

Other objects of the invention will appear hereinafter.

In the drawings, Fig. 1 is a vertical longitudinal sectional view of the pump apparatus;

Fig. 2 a transverse section on the line 2—2 of Fig. 1;

Fig. 3 a transverse section on the line 3—3 of Fig. 1;

Fig. 4 a sectional side view of a portion of the power transmission mechanism, showing it adjusted to neutral or non-stroke position; and

Fig. 5 a face view of the pump unit.

The pump apparatus includes a multi-cylinder pump unit embodying all the parts of the pump proper, and a cooperating power transmission unit operatively connected to the pump unit and embodying all of the mechanism required for transmission of power to the pump plungers to operate them in a desired manner. These units are detachably connected, with the mechanisms in a spaced relation, for reasons which will appear hereinafter.

The power transmission unit will be first described. It includes a fluid-tight casing 1 forming a housing for the working parts of the transmission mechanism and adapted to contain a bath of oil at its bottom to lubricate the mechanism. The mechanism is of the swash plate type. It includes a drive shaft 2 extending horizontally entirely through the interior of the casing and projecting outward through apertures in the opposite end walls of the casing. Formed on or fixed to said walls are annular members 3 and 4 encircling the shaft, and fitted within said

annular members are ball bearing assemblies 5 and 6 rotatably supporting the shaft. Screwed into the annular member 3 outward of the ball bearing assembly 5 there is a closure disk 7. The shaft projects outward through an aperture in 5 the disk and the latter is provided with a sealing packing 8 fitting the shaft. The bearing 5 is designed to resist outward axial thrust on the shaft. The annular member 4 is cup-like and apertured to receive a reduced extremity of the 10 shaft and provided with a sealing packing 9 fitting the shaft. The portion of the shaft within the casing is enlarged and has shoulders abutting the inner raceways of the ball bearing assemblies 15 to hold the shaft against endwise shift. Outside of the casing an electric motor or other source of power, not shown, will be connected to the shaft.

Within the casing 1 there is a tubular swash member 5 encircling the shaft. The shaft has a 20 squared portion 10 to which the swash member is held to rotate with the shaft and also to tilt relatively to the shaft axis. For tiltably mounting the swash member on the shaft the latter has a pair of trunnion pins 11 projecting diametrical- 25 ly from opposite sides of the squared portion of the shaft. Said pins have frusto-conical portions fitted within correspondingly shaped aligning bores in the shaft, and cylindrical portions protruding from the shaft. Interposed between said 30 protruding ends and the swash member there are roller bearing assemblies 12 including inner race members fitted on the ends of the pins and outer race members fitted within the swash member. A bolt 13 extending through aligning axial bores 35 in the trunnion pins holds the frusto-conical portions of the pins seated in the shaft bores.

An annular member 14 encircles the swash member. This member 14 is connected to the swash member to tilt therewith on the shaft, but 40 is held against rotation with the swash member and shaft. The swash member is operatively connected to the member 14 to impart thereto a universal tilting or swash rocking movement so that the member 14 may be termed a follower 45 member. The connections for operating the pump plungers are made through the follower member. For suitable mounting of the latter the swash member is made rather long. It surrounds the squared portion of the drive shaft 50 and also an adjacent cylindrical portion of the shaft and has a portion with a cylindrical periphery 15.

The annular follower member 14 has a disk-like head portion 14a surrounding the trunnioned 55

portion of the swash member, and a tubular shank portion 14^b with a cylindrical interior surface 16 concentric with the peripheral surface 15 of the swash member. Between said surfaces 5 there is a pair of roller-bearing assemblies adapted to resist both radial and axial thrust. They include frusto-conical rollers 17, outer race members 18 fitting the inner surface 16 of the follower member, and inner race members 19 fitting the 10 periphery 15 of the swash member. The rollers of the two bearings are disposed with their axes inclined inward toward each other, for resistance of axial thrust in both directions. A ring 20 disposed between the outer race members of the 15 bearings holds the bearings in a spaced relation, and the inner race member of the bearing nearest the trunnion mounting of the swash member abuts a shoulder 21 on said member. A threaded ring or nut 22 screwed on the remote end of the 20 swash member abuts the inner race member of the adjacent bearing and removably holds both bearings in place. The bearings hold the follower member in a definite relation to the swash member and the two members may be tiltably adjusted 25 as a unit to vary their obliquity to the axis of the drive shaft.

There is provided a mounting to support the follower member for universal tilting by the swash member and hold it against rotation with the 30 swash member about the axis of the drive shaft. Said mounting includes a supporting ring 23 encircling the head 14^a of the follower member. At diametrically opposite points the supporting ring bears trunnion pins 24 disposed on a horizontal 35 axis intersecting the axis of the drive shaft 2 at right angles. Said pins are fixed to the ring and project therefrom into bearing blocks 25. The latter are supported by brackets 26 borne by the adjacent end wall of the casing 1. The ring 23 also bears two fixed trunnion pins 27 projecting 40 inward at diametrical points and on an axis at right angles to the axis of the pins 24. The axes of the pins 24 and 27 lie in a plane including the trunnion axis of the swash member. Pins 45 27 have a swivel fit in bearing blocks 28 and the latter are removably fitted in recesses 29 formed in bosses on the periphery of the follower head 14^a. Said recesses open through the outer face of the follower head for insertion and removal of 50 said bearing blocks.

The brackets 26 borne by the casing have guide forks in which the bearing blocks 25 for the supporting ring trunnions are slidably fitted to 55 shift longitudinally of the drive shaft axis. Back of said forks there are mounted plungers 30 to engage the bearing blocks in the forks. Springs 31 urge said plungers against the blocks. Thereby, through the blocks 25 and the trunnions 24 the ring 23 is pressed rearward to hold the bearing blocks 28 back in the recesses 29 and yieldably maintain the supporting ring in a definite relation to the follower member 14.

The casing end wall bearing the brackets 26 and facing the follower member and its supporting ring bears a number of rigid crosshead guides 32. The latter are of hollow cylindrical form and they are arranged in a circular series and in parallel relation to the axis of the drive shaft 2. 60 In the present instance there are nine of these guides equally spaced in the circular series and opposed endwise to the face portion of the follower head 14^a immediately surrounding the swash member. They define apertures in the 65 casing wall through which extend operative con-

nctions between the follower member 14 and the pump plungers.

Said operative connections include crossheads 33 each having a cylindrical periphery slidably fitting in one of the guides 32. Connecting rods 5 34 operatively connect the follower member to the crossheads. For universal connection said rods have spherical ends. To connect one end of the rods to the follower member the latter is formed with a circular series of sockets 35 whose 10 number and spacing corresponds to that of the crosshead guides. In each socket there is a sectional bearing for an end of one of the connecting rods, including a bearing block 36 with a concave seat for the rear of the spherical end of the rod, 15 and an annular bearing member 37 with a concave seat for the front of said end. The member 37 has a screw-threaded connection with the follower member permitting disconnection of the 20 rod. These bearing structures provide push-and-pull connections between the follower member and the connecting rods. Each crosshead 33 has a socket 38 with a concave bearing seat at its bottom for the opposite end of a connecting rod. A bearing bushing 39, with a concave bearing 25 surface for the rod end, is in screw-threaded connection with the crosshead to detachably hold the connecting rod and provide a push-and-pull connection between the rod and the crosshead. 30 Each crosshead is operatively connected to a plunger of the pump located outside of the casing.

The stroke of the crossheads and the connected plungers is dependent upon the tilt of the swash member S and the follower member 14 upon the 35 drive shaft 2. When said members are disposed in their position of maximum obliquity, as shown in Fig. 1, the maximum stroke will be obtained. When they are disposed, as shown in Fig. 4, with the follower head 14^a and the supporting ring 23 40 in a plane normal to the axis of the drive shaft, stroke will be eliminated and the crossheads and pump plungers will remain in neutral positions as the drive shaft and the swash plate S are rotated.

Means are provided to adjust the obliquity of 45 the swash member and follower according to the stroke required. Upon the drive shaft there is mounted a tubular slide 40 keyed, as at 41, to rotate with the shaft, and slidably end-wise 50 thereon. At one side of the drive shaft the slide bears a transverse pintle 42, and at the opposite side of the shaft the swash member S bears a pintle 43 parallel to said first pintle and mounted in an extension 44 on the rear end of the swash member. Said extension also bears an adjustable stop screw 45 to contact the drive shaft and limit the no-stroke adjustment of the swash member. Between the slide and the swash member there is an operative connection comprising links 47. The latter straddle the shaft and have their opposite ends pivoted on the pintles 42 and 43. Shift of the slide to the left, 55 with reference to Fig. 1, exerts a pull upon said links to tilt the swash member and follower toward neutral or no-stroke position. Shift toward the right exerts a thrust upon the links and increases the obliquity of the swash member and thereby increases the stroke. The links are so disposed as to produce a toggle action in which 60 the mechanical advantage or leverage increases as the slide is shifted toward the right. Contact of the interior of the adjacent end portion of the swash member with the drive shaft limits the 65 70 75

tilt of the swash member. Other suitable stop means may be provided however.

For shifting the slide 40 there is provided mechanism including a rock shaft 48. The latter extends horizontally across the interior of the casing, crosswise of the drive shaft and spaced above it. Bearings 49 borne by the opposite side walls of the casing support the rock shaft and, outside of the casing an operating arm or lever 50 is fixed thereto. The shaft is also supported by an intermediate bearing 51 on a bracket 52 borne by the adjacent wall of the casing. Affixed to the shaft at opposite ends of the latter bearing are depending radial arms 53 with forks 54 at their lower ends. A ring 55 encircles the slide 40 and bears diametrically projecting pins 56. The latter have bearings in blocks 57 slidably fitting in the forks 54. The slide 40 is externally threaded at one end and a nut 58 is screwed thereon to abut one counterbored face of the ring 55. An opposite, counterbored face of the ring abuts a race member of a ball bearing assembly 59 disposed between said face and a shoulder 60 on the slide. Thereby, the ring is held to the slide against axial shift. The ball bearing reduces friction between the ring and slide as the latter is shifted to the right by the thrust of the ring, as the operating arms 53 are rocked. To hold the ring against rotation with the slide it is provided with an upwardly extending radial arm 61 whose upper end is slidably fitted in an under slot of a guide 62. The latter is borne by the bracket 52 and extends parallel to the drive shaft 2.

To afford access to the mechanism within the casing the latter is provided with apertures 1^a, of liberal size, at the top and sides. Plates 1^b are detachably secured to the casing to close said apertures.

The pump unit occupies a position outside of the casing 1 and spaced from the casing wall bearing the cross-head guides 32. Said unit includes a pump body 63 formed in the present instance of a single, integral metal block. Said block has a flat, substantially rectangular vertical face 64 (which may be termed the rear face) flat, horizontal top and bottom faces 65 and 66 respectively, and flat, vertical side faces 67. The front face of the block is of a stepped form, for a purpose which will appear herein-after. At its rear face the block has a circular series of bores 68 to form the pump cylinders. Their number corresponds to the number of crosshead guides, and their axes are similarly spaced around a circle of the same diameter as that including the axes of the cylindrical cross-head guides. The bores are all parallel and horizontal and terminate short of the front face of the block. For a portion of their length adjacent the front face they are of reduced diameter to provide a shoulder 69. A bushing 70, fitted in the larger portion of each bore, bottoms against said shoulder. These bushings form the actual pump cylinders. They are in the present instance much shorter than the bores. For a length adjacent the rear face of the block the bores are screw threaded.

Forward of the series of bores 68 the block 63 has a pair of bores 71 and 72 forming the intake and discharge conduits respectively of the pump unit. These bores are parallel and they extend crosswise horizontally from one side face 67 to the other. Conduit 71 is spaced materially below conduit 72 and farther toward the front and the stepped form of the front face of the block pro-

vides a flat horizontal surface 73, at one level, overlying the conduit 71, and a similar surface 74, at a higher level, overlying the conduit 72. In the present instance there are nine of the pump cylinder bores and each is in fluid communication with both conduits 71 and 72. To form said communication the block 63 has nine parallel horizontal bores 75 arranged in a straight row extending crosswise of the front face of the block. They extend straight rearward from the front face at a level midway between the conduits 71 and 72. At the front face they are plugged. Each cylinder bore 68 communicates with one of the bores 75 through an individual bore 76 formed in the block. In the present instance five of the bores 76 extend straight downward from the top surface 65 of the block, two extend straight upward from the under surface 66 and two extend obliquely from the side faces 67 of the block. At the outer surfaces of the block all of said bores 76 are plugged. From the surface 74 of the block a row of vertical bores 77 extend downward, across the discharge conduit 72 and thence to the horizontal bores 75. Similarly, a row of vertical bores 78 lead downward from the surface 73 of the block and across the bores 75 to the inlet or suction conduit 71.

Fitted in each bore 77 there is a valve bushing 79, between the conduit 72 and one of the bores 75. At its upper end said bushing has a beveled seat for an upwardly opening check or poppet valve 80. These valves control communication between the pump cylinders and the discharge conduit 72. Each bore 77 is threaded along its upper end portion and a plug 81 is screwed into it, and provided with a head protruding from the surface 74 of the block. The plug may also have a depending guide for a stem on the poppet valve therebeneath. The valve may be readily withdrawn upward through the bore 77 upon removal of the plug. A bushing 81^a is fitted in each bore 78 between the bore 75 and the inlet conduit 71, and has a beveled seat for an upwardly opening check or poppet valve 82. The valves 82 control communication between the pump cylinders and the inlet conduit 71. Each bore 78 is threaded along its upper end portion, and a plug 83 is screwed into it and has a head protruding from the surface 73 of the block. The valves 82 may be readily withdrawn upward through the bores 78 upon removal of the plugs 83. Removal of the plugs 81 and 83 also renders the valves 80 and 82 accessible for grinding them in place. The conduits 71 and 72 are screw-threaded at their opposite ends. A supply pipe 84 may be connected to either end of the conduit 71 in the block and the other end of the conduit closed by a threaded plug 85. Similarly, a discharge pipe 86 is connected to one end of the conduit 72 in the block, and the opposite end of the conduit is closed by a threaded plug 87.

Plunger rods 88 are fitted to reciprocate in the pump cylinders 70 and extend outward through the open rear ends of the bores 68. Headed, screw-threaded bushings or glands 89 fitting the plungers are screwed into said ends of the bores 68 and bear against suitable packing 90 surrounding the plungers, between said bushings and the cylinder-forming bushings 70. Each crosshead 33 is operatively and detachably connected to one of the pump plungers. The crosshead has a screw-threaded axial socket 91 in its outer end, and the plunger has a screw-threaded end 92 screwed into said socket. The plunger also has an enlarged portion 93 abutting the end of the

5

75

crosshead and formed for engagement by a wrench.

The pump unit is detachably supported in operative relation to the power transmission unit by tie rods 94. In the present instance there are four of said rods in rectangular arrangement and extending in parallel relation through both of said units. They pass through apertured bosses 95 on the opposite end walls of the casing 1 and though bores 96 in the pump block 63. Between the pump block and casing 1 the tie rods have enlarged spacing portions 94a affording end shoulders to abut the rear face of the pump block and the adjacent bosses 95 and support the pump unit 15 in a definite spaced relation to the transmission unit. The opposite ends of the tie rods are threaded, and nuts 97 are screwed thereon to abut the front face of the pump block and the bosses 95 on the far end of the casing 1 and anchor the units in said relation. The tie rods support the pump and resist the pressure exerted upon the pump block by the pumping action. At its end adjacent the pump unit the casing 1 has a trough-like extension 98 to catch leakage from the pump cylinders. Said extension has an end wall 99 engaging the under side of the pump block and affording additional support for the latter.

In the operation of the pump apparatus, assuming that the swash member is adjusted in a 30 tilted relation to the drive shaft 2, the rotation of the shaft will cause a swash rotation of said member and the follower member 14 will receive a universal swash rocking movement from the member S. Said rocking movement is transmitted to the follower member from the swash member 35 through the inclined roller bearings between said members. Since the follower member is held by its universal mounting against rotation with the swash member the latter by cam action rocks the follower member to reciprocate the connected crossheads 33 and pump plungers 88 in a manner to obtain continuous discharge through the pump conduit 72. Referring to Fig. 1, the plunger at the top is withdrawn by the follower member 40 45 14 to the limit of its suction stroke, while the plunger at the bottom is pressed forward to the limit of its compression stroke. The plungers in between are in intermediate stroke positions. Rotation of the swash member and universal 50 55 rocking of the follower member thereby will advance this relation of diametrically disposed plungers around the drive shaft axis so that the plungers will all be operated simultaneously but out of phase for constant delivery.

55 Upon the suction stroke of a plunger, fluid in the conduit 71 forces open one of the poppet valves 82 and flows to the pump cylinder through the connected bores 75 and 76, the suction holding the poppet valve 80 closed. Upon the pressure stroke of the plunger the fluid is forced out of the pump cylinder, through the bores 76 and 75, and past the valve 80 to the discharge conduit 72, the pressure of the fluid holding the valve 82 closed.

60 The pump apparatus is designed for efficient operation and for ready accessibility of working parts, enabling the apparatus to be easily kept in good working condition. The customary type of pump operated by a swash plate mechanism 65 is of a design requiring rotation of the pump unit. That entails valving complication. It also necessitates a close inter-relation of the power transmission mechanism and the pump, rendering working parts difficult of access and also permitting the fluid in the pump cylinders to leak over

the transmission mechanism. For the latter reason it is necessary to employ oil as the pumping fluid in such a pump. My improved pump apparatus avoids said objectionable features. The improved design of the power transmission mechanism enables a cooperating fixed pump unit to be employed, with consequent simplification of the valving. It enables the pump unit to be mounted in a desirable spaced relation to the power transmission mechanism, thereby preventing leakage from the pump cylinders to said mechanism and enabling water to be employed as the pumping fluid, if desired. All of the working parts of the pump are rendered readily accessible and removable so that they may be kept in good working condition. The plugs 81 and 83, over the discharge and intake valves of the pump have heads freely exposed in straight rows and in stepped relation, to facilitate engagement by a wrench, to unscrew the plugs and to get at 10 15 20 the valves.

Another desirable feature is the removability of the pump unit en bloc from the power transmission unit without disturbing any parts of the latter. The pump unit may be readily detached by unscrewing the nuts 97 at the front face of the pump and unscrewing the plungers from the crossheads 33. The crossheads then remain part of the transmission assembly and the mutual fit of the crossheads and their guides 32 prevents escape of lubricating oil from the casing 1 and also prevents entrance of water into the casing. Different pump units, possibly of different capacity, may be interchangeably connected to a single transmission unit.

35 What I claim is:

1. A pump unit comprising a plurality of pump cylinders and plungers arranged in a series around a circle and disposed in parallel relation, straight parallel outlet and inlet conduits disposed transversely of the longitude of the pump cylinders and plungers, fluid communications between the pump cylinders and said conduits at points spaced along the latter, a row of valves along each conduit to open and close said communications, the conduits having apertures spaced therealong for insertion and removal of said valves, and removable plugs closing said apertures.

2. A pump unit comprising an integral block 50 with a plurality of parallel bores for pump cylinders arranged in a circular series, and with a pair of straight parallel bores extending crosswise of said series and spaced from one end of the bores in the series, said pair of bores forming outlet and inlet conduits and the block having bores forming fluid communications between the bores of the circular series and said conduits at spaced points along the latter, a row of check valves along each of said conduits to control said communications, the block having a pair of external surfaces in stepped relation for the purpose set forth extending along said conduits and rows of threaded bores opening from the conduits through said surfaces for insertion and removal of said valves, and screw plugs closing said threaded bores.

3. A pump unit comprising a block with a plurality of parallel bores for pump cylinders arranged in a circular series, and with a pair of straight parallel bores extending crosswise of said series and spaced from one end of the bores in the series, said pair of bores forming outlet and inlet conduits and the block having bores forming fluid communications between the bores of 60 65 70 75 80 85 90

the circular series and the said conduits at spaced points along the latter, a row of check valves along each of said conduits to control said communications, the block having rows of bores opening transversely from the conduits to the exterior of the block for insertion and removal of said valves, and removable closures for said latter bores.

4. A pump apparatus including in combination, a power transmission unit comprising a casing to contain an oil bath, a driving swash member mounted for rotation in said casing, a follower member in the casing extending around the axis of rotation of said driving member and operable thereby and held against rotation about said axis and mounted for universal swash rocking by the driving member; a pump unit exposed at the exterior of said casing and mounted in a position spaced from an outer wall of the casing and having pump cylinders, plungers in said cylinders, packings for said plungers, and valves to control flow through the pump unit and including a series of inlet valves and a series of outlet valves, the pump unit having a straight horizontal row of apertures opening upward through an outer wall of the pump unit at one level and through which the inlet valves are insertible and removable and a parallel row of apertures opening upward through an outer wall of the pump unit at another level and through which the outlet valves are insertible and removable and said rows being transverse to the pump cylinders and at the end thereof remote from the transmission unit, the cylinders opening into the space between the pump unit and said casing wall and the wall having apertures opening into said space; and operative connections between said follower member and the pump plungers extending through said casing wall apertures, the latter apertures being sealed against passage of fluid therethrough past said operative connections.

5. A pump apparatus comprising a casing adapted to contain an oil bath, a drive shaft extending through said casing, a swash member within the casing and tiltably mounted on said shaft, a follower member within the casing and mounted on the swash member for universal swash rocking thereby and held against rotation therewith about the shaft axis, said swash member being of elongated tubular form, encircling the shaft and being pivotally connected to the shaft for tilting on an axis transverse to the shaft, a swash adjusting member disposed within the casing and mounted on the shaft to shift therewith, a pull-and-thrust linkage connection pivoted at one end to said adjusting member and pivoted at its opposite end to the swash member at a point spaced materially along the swash member from the pivotal connection of the latter with the shaft and arranged in an angular relation to the shaft to constitute with the swash member a toggle mechanism to tiltably adjust the swash member by shift of said adjusting member and with increasing mechanical advantage as the tilt is increased by shifting of the adjusting member toward the pivot of the swash member on the shaft, the follower member being annular and having anti-friction bearings between it and the swash member to resist radial and axial thrust, a wall of the casing opposed to a face of the follower member having apertures, and crossheads slidably mounted in said apertures and having their outer ends exposed to the exterior of the casing and releasably connectible at the exterior of the casing to pump plungers, said follower member being operatively connected at points around the shaft axis to said crossheads.

6. A pump driving apparatus comprising a casing adapted to contain an oil bath, a drive shaft extending through said casing, a swash member within the casing and tiltably mounted on said shaft, a follower member within the casing and mounted on the swash member for universal swash rocking thereby and held against rotation therewith about the shaft axis, said swash member being of elongated tubular form, encircling the shaft, and being pivotally connected to the shaft for tilting on an axis transverse to the shaft, a swash adjusting member disposed within the casing and mounted on the shaft to shift therewith, a pull-and-thrust linkage connection pivoted at one end to said adjusting member and pivoted at its opposite end to the swash member at a point spaced materially along the swash member from the pivotal connection of the latter with the shaft and arranged in an angular relation to the shaft to constitute with the swash member a toggle mechanism to tiltably adjust the swash member by shift of said adjusting member and with increasing mechanical advantage as the tilt is increased by shifting of the adjusting member toward the pivot of the swash member on the shaft, the follower member being annular and having anti-friction bearings between it and the swash member to resist radial and axial thrust, a wall of the casing opposed to a face of the follower member having apertures, and crossheads slidably mounted in said apertures and having their outer ends exposed to the exterior of the casing and releasably connectible at the exterior of the casing to pump plungers, said follower member being operatively connected at points around the shaft axis to said crossheads.

7. A pump apparatus comprising a casing adapted to contain an oil bath, a drive shaft extending through said casing, a tubular swash member pivotally mounted on and encircling the shaft within the casing to tilt on an axis transverse to the shaft, an annular follower member within the casing and encircling the swash member transversely of the said shaft and formed with a tubular portion surrounding the swash member, anti-friction bearings between the tubular portion of the follower member and the swash member to resist radial thrust and axial thrust in either direction, the follower member being arranged close to an end wall of the casing and the tubular portion thereof extending away from the said end wall, means holding the follower member against rotation about the said shaft, a circular series of sliding crossheads mounted in said end wall of the casing their outer ends being exposed outside of the casing, a connecting rod between the inner end of each of said crossheads and the follower member, a pump adjacent said end wall of the casing and including pump plungers operatively connected to the exposed outer ends of the crossheads and extending into the pump casing, a swash adjusting member within the casing and mounted on the shaft to shift therewith, and a pull-and-thrust linkage connection pivoted at one end to said adjusting member and pivoted at its opposite end to the

- swash member at a point spaced materially along the swash member from the pivotal connection of the latter with the shaft and arranged in an angular relation to the shaft to constitute with 5 the swash member a toggle mechanism to tiltably adjust the swash member by shift of said adjusting member and with increasing mechanical advantage as the tilt is increased by shifting of the adjusting member toward the pivot of 10 the swash member on the shaft.
8. A pump driving mechanism comprising a drive shaft, a swash member mounted on said shaft, a follower member mounted on the swash member for universal swash rocking thereby, held 15 against rotation therewith about the shaft axis and operatively connectible to pump plungers at points spaced around the shaft axis, a gimbal ring

surrounding the shaft axis and having inwardly extending trunnions diametrically arranged, said follower member having bearing recesses for reception of said trunnions and open at one side in the direction of the shaft axis for entry of the 5 trunnions, said gimbal ring having opposite outwardly extending trunnions on a diameter at a right angle to said first trunnions, bearing members rotatably receiving said outwardly extending trunnions, fixed guides supporting said bearing members for shifting of the same along the shaft axis, and springs urging said bearing members along their said guides to urge the gimbal ring along the shaft axis to hold said inwardly extending trunnions pressed into said bearing 10 recesses of the follower member.

FRANK L. DAVIS, JR.
